ELECTRIC SWITCH

Johann G. Peterson, West Hartford, Conn.

Application November 8, 1934, Serial No. 751,995

25 Claims. (Cl. 200—70)

My invention relates to electric switches. It has among its objects to provide an improved switch especially adapted to use in portable electric hot plates, or ranges, wall switches, or the like, and, more particularly, an improved switch of this type having spaced "on" positions and a central "off" position. A further object of my invention is to provide an improved switch of this type which, as compared with previous switches of this type, is of an improved and markedly more compact construction, while of increased capacity, as compared with previous switches of this size. Other objects of my invention are to provide such an improved switch requiring only a single spring and having improved cam mechanism and improved automatic means for insuring the throwing of the switch, as well as an improved structure and arrangement of the commutator contacts and contact carrying parts, whereby all of the insulation is in the commutator and a terminal carrying cover while all of the rest of the mechanism and casing is "dead" in such manner as to eliminate any need for an outer insulating casing. Further objects are the production of such an improved switch which despite its small size is of such character as to meet the underwriter's requirements previously incapable of being met in switches of this size, and also to provide a switch which is adapted to be manufactured at substantially smaller expense than other switches of this class previously produced. These and other objects and advantages of my improved construction will, however, hereinafter more fully appear.

In the accompanying drawings I have shown for purposes of illustration one embodiment which my invention may assume in practice.

In these drawings,—

Figure 1 is a front view of my improved switch; Fig. 2 is a plan view of the switch shown therein, the insulating terminal plate being exposed and the actuating member being illustrated in different positions in full and dotted lines;

Fig. 3 is a side elevation of the switch of Figure 2, the face plate being omitted;

Fig. 4 is an end view of the switch shown in Figure 3, the actuating member being swung to the right into the "on" position;

Fig. 5 is a sectional view on line 5—5 of Figure 2, the view being substantially enlarged as compared with that figure;

Fig. 6 is a sectional view on line 6—6 of Figure 2, this view also being on the scale of Figure 5;

Fig. 7 is a detail-sectional view on line 7—7 of Figure 6;

Fig. 8 is a view similar to Figure 2, with the insulating terminal carrying cover removed to expose the contact carrying commutator;

Fig. 9 is a view similar to Figure 8, but with the commutator lifted off to expose the commutator actuating mechanism;

Fig. 10 is a view similar to Figure 9, but with the latter mechanism lifted off to expose the operating mechanism carried by the actuating member;

Fig. 11 is a plan view of the opposite side of the terminal and contact carrying plate from that shown in Figure 2;

Fig. 12 is an enlarged detail side elevational view of the commutator actuating mechanism;

Fig. 13 is a view of the latter at right angles to Figure 12, and

Fig. 14 is a bottom plan view of the mechanism shown in Figures 12 and 13.

In this construction, it will be noted that I have shown my improved switch disposed in a frame or casing member 1 housing a suitable commutator, generally indicated at 2 and carrying a multiplicity of contacts cooperating with contacts carried on a cover plate 3, which in turn carries suitable terminals, the casing 1 herein having a suitable face plate 4 attached thereto and the switch mechanism having an actuating member 5 projecting through a slot 6 in this plate 4 and operatively connected to actuate the commutator 2 with a snap action through improved mechanism hereinafter described.

Referring more particularly to the casing 1, it will be noted that this casing 1 herein is preferably made entirely of metal and comprises a bottom portion or plate 7 and upstanding spaced sides 8, while both ends are open, and oppositely extending lateral lugs 9 are provided on the end adjacent the actuating member to provide connecting means for screws 10 connecting the face plate 4 thereon. Herein also, the sides 8 are provided with openings 11 therein beyond which the contacts on the commutator 2 extend, as indicated in Figure 6, while posts 12 at opposite ends of each side are provided with upstanding lugs or extensions 13 thereon which are adapted to be bent over, as shown in Figure 2, to position the terminal carrying plate 3 and hold the parts assembled to form a unitary structure.

Referring more particularly to the switch mechanism which is carried in the casing 1, it will be noted that the same includes a notched plate 14 resting flat on the bottom 7 inside the latter and suitably attached thereto as by rivets 15. Herein this plate 14 is cut out to provide a

central flat bottomed, round recess 16 having a series of peripheral, rectangular notches 17, 18 and 19 disposed on opposite sides thereof and spaced from one another, as illustrated in Figure 5 10, with the bottom of each notch preferably disposed as herein in the same plane as the bottom of recess 16. Disposed axially of this recess 16 is a stud 19' suitably fixed at its lower end in the bottom 7 and projecting upward therefrom to a 10 point slightly beyond the top of the insulating plate 3. Further, rotatably mounted on this stud is a hub portion 20 on the actuating member 5, which rests flat on the bottom of the recess 16 and is movable therein to permit the member 5 15 to occupy any of the three positions illustrated in Figure 2. Herein it will also be noted that the actuating member 5 is slightly raised with respect to the hub portion as by bending up the shank of the actuating member so that it moves above 20 the adjacent portion of the plate 14. As shown, the hub 20 also carries oppositely disposed arms or projections thereon having flat bottoms turning on the bottom of the recess 16 and rounded tops forming cams 21 which rotate with the 25 member 5 and hub 20 from the dotted line position indicated at A in Figure 10 through the full line position illustrated therein to the dotted line position indicated at B in that figure to actuate the contacts and ratchet as hereinafter described. 30 Moreover, it will be noted that the hub portion 20 has thereon an upstanding member or lug 22 on the side thereof diametrically opposite the actuating member 5 and that this lug projects upwardly a substantial distance, as illustrated in 35 Figure 5, to permit it to cooperate with other elements of improved switch actuating mechanism hereafter described.

Referring more particularly to the actuating mechanism, it will be noted that the same includes a combined cam and contact actuating mechanism herein including a member 23 journaled as at 24 on the stud 19' just above the hub portion 20. Moreover, it will be noted that this member 23 is provided with a pair of upstanding 45 parallel arms 25 on opposite ends thereof and having bent upper ends 26 carrying upstanding projections 27 on their extremities. Herein it will also be observed that a cam carrying member 28 is seated on the member 23 between the arms 25 and that this member has spaced lugs 29 at each side thereof disposed on opposite sides of one of the arms 25. Moreover, at right angles to these lugs and also on each side of the member 28, cam carrying wing members, generally indicated at 30 are provided which extend outward and then downward in opposite directions laterally in such manner as to overlie and extend to opposite sides of the cam members 21 on the hub 20 of the actuating member 5. It will be observed that the members 30 are provided with oppositely sloping spaced cam surfaces 31 adapted to be engaged and cooperate with these members 21, while the members 30 are also provided between the cam surfaces 31, but on the peripheries 55 of the members 30 beyond these surfaces 31, with depending lugs 32 adapted to be received in different positions in the notches 17, 18 and 19, and to move vertically into and out of said positions. Acting upon the hub of the member 28 at one end 60 and disposed coaxially outside a sleeve 33 fixed to the member 23 and extending up through the member 23, is a single coiled spring 34, the opposite end coils of which engage the hub of the member 23 and a washer which is carried by the sleeve 33 and herein positioned by a removable 65

notched spring washer 35 suitably seated in a groove 36 in the upper end of the sleeve, while the latter is also positioned by a like washer 33' on the post 19'. Moreover, it will be noted that the spring 34 has its opposite extremities extended laterally in the same direction on opposite sides of the upstanding projection 22 on the hub 20 and the adjacent arm 25 on the member 23. Thus, this spring is tensioned by the projection 22 whenever the actuating member 5 is moved about the stud 19' as an axis while also being compressed by the member 28 as the latter moves upward. Accordingly, whenever the actuating member 5 is swung to swing the cam members 21 and thereby raise the cams 21 and raise the lugs 15 32 vertically and release the same from any pair of the notches 17, 18, 19, this single spring acts to swing the member 23 about the stud 19' as an axis laterally with a snap action through connections hereinafter described and thereby swings 20 the movable commutator 2, while also forcing the member 28 and lugs 32 down in each new lateral position thereof to seat said lugs in the proper notches 17, 18 or 19.

Referring more particularly to the commutator 2, it will be noted that the latter is rotatably mounted on the stud 19' above the washer 33' and that the commutator 2 has improved means for rotating the same thereon as the arms 25 are rotated by the spring 34 upon movement of the 30 actuating member 5. More particularly, it will be noted that the projections 27 on the arms 25 are received in oppositely located notches 38 in the commutator member 2, so that the commutator 2 will move in either direction with a 35 snap action as the lugs 32 move between different positions relative to the notches 17, 18, 19. It will also be noted that the commutator herein is in the form of a single thin insulating disc and has an elongated axial eyelet or sleeve 39 therein 40 journaled on the stud 19', and an outer shorter sleeve 39' attached to the outside of the upper end of the eyelet 39 by turning over the upper end thereof. This commutator disc herein also has a plurality of multiple contact members 40 45 thereon, herein superimposed in pairs disposed on opposite sides of a central line passing through the center of the notches 38. Herein it will also be noted that each of these four contact members 40 is identical, and that two of the latter are provided on each face of the commutator. Moreover, each has projecting contacts 41, 42, 43 or 41', 42', 43' overlying like contacts on its companion member 40 disposed on the opposite side of the commutator disc 2, while the two co- 50 operating members 40 on each side of the center line are suitably connected to each other and the disc 2, as, for example, by rivets 40'. Thus it will be noted that on each side of the center line mentioned, three pairs of spaced contacts of some 55 resiliency are provided projecting radially from the disc and spaced from one another in such manner as to enable each pair to receive between them in different rotative positions of the commutator, a cooperating stationary contact hereinafter described and carried on the cover or terminal plate 3. Moreover, it will be noted that the contacts 41, 42, 43, or 41', 42', 43' are disposed at equal distances from one another, and that the same are free to move in opposite directions 60 about the axis of the stud 19' as the commutator 2 is caused to be moved in either direction with a snap action by the actuating mechanism therefor, heretofore described, and actuated by the movement of the actuating member 5. 75

Cooperating with this commutator 2 are also improved stationary contacts. Herein these contacts are carried on the cover plate 3, which is also a thin insulating plate, and these contacts comprise a plurality of stationary contact portions 44, 45, 46, 47 and 48 disposed parallel to the plate 3 and spaced therefrom, as illustrated in Figure 3. As shown, each contact portion is connected to the plate by a suitable terminal shank 49 extending upward through a suitable aperture 50 in the plate 3, and each shank also has a laterally deflected terminal portion 51 thereon on the outer face of the plate 3 and provided with oppositely located down turned portions 52 extending down through suitable apertures 53 in the plate and turned over on the inside of the latter as shown at 54. Here also it will be noted that binding screws 44', 45', 46', 47' and 48' are carried on these terminal plates to enable the connections of conductors for the contacts 44, 45, 46, 47 and 48. Attention here is also directed to the fact that the apertures 50 for the shanks 49 are elongated as shown in Figure 11 to permit both each shank 49 and each adjacent binding screw to extend downward through opposite ends of the same aperture. Also, it will be noted that the cover plate 3 is suitably positioned on the stud by a removable washer 55, similar to the washers 35 and 33', and receivable in a suitable groove in the end of the shaft. Herein, it will also be observed that the cover plate 3 rests on a like washer 56, below the same and similarly seated in the stud and which in turn forms an abutment for the upper end of the sleeve or eyebolt 39, the structure thus being such as, with the overturned ends 43, effectually to prevent displacement of the stationary contacts relative to the commutator.

In the operation of the switch, it will be evident that, assuming the actuating member 5 to be in its central "off" position illustrated in full lines in Figure 2, the switch mechanism will be actuated when the member 5 is moved into any of the positions shown in that figure. With the parts in "off" position, the actuating member 5 and cams 21 will be in the position shown in full lines in Figure 10, while the commutator will be in the position illustrated in Figure 8, and the commutator actuating mechanism actuated by the cam members 21 and upstanding projection 22, will be in the position shown in Figure 9. More particularly considering the operation and assuming the actuating member 5 to be swung from its central "off" position toward the upper dotted line position shown in Figure 2, the cams 21 will move counter-clockwise from the position shown in Figure 10 into engagement with diagonally disposed cam surfaces 31 on the member 30 in such manner as to raise the latter vertically and thereby cause the depending lugs 32, which are then in engagement with oppositely located central notches 18, to be raised above those notches. As these lugs 32 are being thus raised to release the member 30, it will be noted that the spring 34 is both tensioned and compressed, the same being tensioned by the movement of the projection 22 relative to the adjacent lug 25 and being compressed by the vertical movement of the member 28 by the cam members 21. As a result, when the lugs 32 are lifted clear of the notches 18, the member 28 will be swung by the spring 34 from a position over the notches 18 to a position over the notches 17 with a quick snap action, and, when over the latter notches, the depending lugs 32

on the member 30 will be forced down as the compression on the spring 34 is relieved, in such manner as to seat these lugs in the notches 17. Further, it will be evident that as the member 28 is thus swung with a snap action, it will similarly swing the member 23, while the latter being connected through the extension 27 on its upstanding arms 25 with the commutator 2, the latter will be rotated in a counter-clockwise direction with a quick snap action from the position shown in Figure 8 into its next position. More particularly, it will be observed that in this latter position, the movable contact 43 has swept over both sides of stationary contact 44 into engagement therewith, while movable contacts 42, 41, 41', 42', similarly engages stationary contacts 45, 46, 47, 48, respectively, and movable contact 43' is then out of contact with any stationary contact and disposed in alignment with the longitudinal or "off" position of the actuating member 5. Obviously, when the member 5 is reversely moved from the upper dotted line position shown in Figure 2 back to the central "off" position shown in full lines in that figure, the parts will be reversely operated to return the same automatically and with a snap action, while if the actuating member 5 is then moved to the other dotted line "on" position shown in Figure 2, the parts will be operated similarly, it being understood that when the actuating member is swung in one direction, herein toward the upper dotted position, the commutator 2 will be swung counter-clockwise, while when the member 5 is moved in the opposite direction, the commutator 2 will be swung clockwise, and that in either position one of the movable contacts on the commutator will engage the contact 46. Further, it will be evident that in either dotted line position, all of the movable contacts save one will be in engagement with a stationary contact, and that the movable contact then not in use will alternate between the movable contacts 43 and 43', depending upon the direction of movement of the actuating member 5, movable contact 43' being the inactive contact when actuating member 5 is moved to the upper dotted line position of Figure 2 and movable contact 43 being the inactive contact when the actuating member 5 is moved to the lower dotted line position shown in that figure.

As a result of my improved construction, it will be noted that it is made possible for the single spring 34 to function not only as the actuating means for actuating the movable contacts 43 with a quick snap action beyond the control of the operator moving the actuating member, but also to actuate the movable member 28 which carries the depending lugs 32 of the ratchet mechanism which comprises these lugs and the notches 17, 18 and 19, the structure being such as to compress this spring 34 at the same time that the latter is tensioned and thereby enable it not only to swing the movable contacts as described but also to seat the lugs 32 in their new positions relative to the notches. Here attention is also directed to the fact that the actuation of the parts is not only such that the same will move with certainty from one position to another, but the arrangement of the raised portion 20 on the shank of the actuating member 5 is such relative to the bent down ends of the cams 31 that, should there be any sticking of the contacts, this shank portion will engage the portion of the exterior of the adjacent cam 31 in such

manner as to provide a positive kick off for the same and the connected mechanism which is available in all movements of the actuating member 5. Furthermore, it will be observed that the structure including the stationary central stud and the coaxially disposed elements rotatable relative thereto, is an exceedingly simple one and one which requires only a small number of parts and parts which are of a rugged construction and adapted to long operation without appreciable wear while being capable of being cheaply produced. It will also be observed that the structure is exceedingly compact and that, despite its compactness, it has a current capacity 10 substantially greater than it has heretofore been possible to obtain in a switch of the same size. Attention is also directed to the fact that all of the mechanism save the movable and stationary contacts carried by the insulating plates, is dead 15 electrically, so that the structure is not only safe but such as to permit it to be used without any necessity for an outer insulating casting such as has heretofore been provided in switches of this type. It will also be evident that with this construction, it is possible to vary the wiring or circuit connections readily within wide limits, as, for example, by connecting conductors to the terminals in such manner that, in one end position, the switch is adapted to connect the 20 circuits for a high heat, while in the other end position a low heat is provided, or so that either circuit may be "on" while the other is "off", or one circuit may be "on" in one end position and in the other end position two circuits will be 25 "on", all in such manner as to make the same adapted to use under a wide range of conditions as, for example, either in portable hot plates or ranges or wall switches or the like. Further, as regards size and cost, it will be apparent that 30 the improved switch occupies substantially less space and can be furnished at a fraction of the cost of other switches heretofore believed to be required to meet the Underwriter's requirements on portable hot plates and electric ranges. These 35 and other advantages of my improved construction will be clearly apparent to those skilled in the art.

While I have in this application specifically described one embodiment which my invention 50 may assume in practice, it will be understood that this form of the same is shown for illustrative purposes and that my invention is not limited to this embodiment but may be modified and embodied in other forms without departing from 55 its spirit or the scope of the appended claims.

What I claim as new and desire to secure by Letters Patent is:—

1. An electric switch having movable contact mechanism, cooperating releasable mechanism 60 for holding said contact mechanism in its different positions, and actuating mechanism including an actuating member movable in reverse directions and having a single spring compressed and tensioned upon operation of said ratchet 65 mechanism and having the compression and tension forces thereof actuating said holding and contact mechanisms respectively when said member is moved in either direction.

2. An electric switch having movable contact 70 mechanism, cooperating releasable mechanism for holding said contact mechanism in its different positions, and actuating mechanism including an actuating member movable in reverse directions, a single spring, and means operable 75 when said actuating member is moved in reverse

directions for tensioning and releasing said spring to actuate the movable contact mechanism therefrom and compressing and releasing said spring to actuate said holding mechanism therefrom.

3. An electric switch having movable contact mechanism, cooperating ratcheting mechanism having stationary and movable ratchet elements, and actuating mechanism including an actuating member movable in reverse directions and having a single spring operatively connected to actuate said actuating mechanism and move said movable ratchet element relative to said stationary ratchet element when said member is moved in either direction.

4. An electric switch having movable contact 15 mechanism, ratcheting mechanism comprising a stationary ratchet member and a relatively vertically movable ratchet member cooperating with said stationary member for positioning said contact mechanism in different positions, and actuating mechanism including an actuating member movable in reverse directions for releasing said movable ratchet member, said actuating mechanism having a single actuating spring also operatively connected between said movable ratchet 20 member and actuating member and moving said movable ratchet member vertically relatively to said stationary ratchet member.

5. An electric switch having movable contact 30 mechanism movable in reverse directions, cooperating ratcheting mechanism therefor, a single spring, and means operable in reverse directions for tensioning and releasing said spring to actuate the movable contact mechanism therefrom and compressing and releasing said spring to 35 actuate said ratcheting mechanism therefrom.

6. An electric switch having movable contact means, ratchet means controlling the latter and including a stationary and a cooperating movable ratchet element, mechanism for releasing 40 said ratchet means while said contact means is stationary, and operative connections actuated by said mechanism having a single spring for thereafter moving both said movable contact means and said movable ratchet element relative 45 to said stationary ratchet element.

7. An electric switch having movable contact means, ratchet means controlling the latter and including an axially movable element, cam mechanism for releasing said ratchet means while said 50 contact means is stationary, and operative connections actuated by said mechanism having a single spring for thereafter moving both said movable contact means and said movable ratchet element into new positions, said spring being both 55 tensioned and compressed upon operation of said cam mechanism and released upon release of said ratchet means.

8. An electric switch having movable contact mechanism movable in fixed planes, ratchet 60 mechanism positioning the same in different positions having an axially movable element, an actuating member, and means including a single spring tensioned and compressed upon movement of said actuating member for moving said 65 movable contact mechanism in said planes into a new position and actuating said axially movable element of said ratchet mechanism to hold said contact mechanism in the new position.

9. In a switch, contact mechanism having a 70 stationary member and a rotary member held against axial movement, ratchet mechanism having a stationary member and a rotary member which is axially movable, a rotary transmitting member actuated by said movable ratchet mem- 75

ber for turning the rotary contact member, and actuating mechanism for the ratchet mechanism having a single coil spring which is tensioned for turning the movable ratchet member and compressed for reseating said member.

10. In a switch, a reversely movable cam member, ratcheting mechanism including a movable ratcheting member cooperating with said cam member in either direction of movement thereof, and contact swinging and ratchet releasing and seating mechanism operative in either direction of movement of said cam member including a member movable with said cam member, a co-operating member movable with said movable ratcheting member, and a spring acting on both of said last named members and both tensioned and compressed upon movement of said cam member.

11. In a switch mechanism, a ratchet plate, a movable cam, a spring pressed cam cooperating with said cam and having projecting means co-operating with said ratchet plate, movable contact means relative to which said cam is movable, means for swinging said means with said spring pressed cam when the latter is disengaged from said ratchet plate, and means for positively actuating said spring pressed cam should said contact means not be completely swung by said swinging means.

12. In a switch, a frame having a bottom and a cover, a swinging actuating member pivoted on said frame, snap actuating mechanism actuated by said actuating member and carried by said bottom within said frame, a rotary commutator fixed against movement along its axis in said frame and disposed in planes parallel to the path of said swinging member and actuated by said snap actuating mechanism and carrying a series of contacts extending radially in opposite directions from said axis, and stationary contacts carried by said cover cooperating with the contacts on said commutator.

13. In a switch, a frame, an actuating member extending into said frame, snap actuating mechanism actuated by said actuating member and within said frame, a rotary commutator fixed against axial movement in said frame and actuated by said snap actuating mechanism and carrying a plurality of laterally projecting contacts extending radially in opposite directions from said axis, a cover plate of insulating material carried by said frame, and stationary contacts carried by said cover plate and having depending portions extending within said frame and between contacts on said commutator.

14. In a switch, a frame, a swinging actuating member pivoted on said frame, snap actuating mechanism actuated by said actuating member and within said frame, a rotary commutator fixed against axial movement in said frame and actuated by said snap actuating mechanism in planes parallel to the path of said swinging member, and stationary contacts carried by said frame co-operating with the contacts on said commutator, said commutator carrying a plurality of series of contacts insulated from one another and said stationary contacts including a contact engaged by one contact of one series in one position of said actuating member and by a contact of another series in another position of said members.

15. In a switch, a casing having upstanding sides and a bottom and an open top, an actuating member extending into said casing, snap actuating mechanism within said casing including a spring means actuated by said actuating mem-

ber, said actuating mechanism being carried on the bottom of said casing, a commutator within said casing, and carrying movable contacts actuated with a snap action by said spring means of said actuating mechanism, and a cover plate closing the open top of said casing and carried by said sides having on said cover plate stationary contacts independent of said actuating mechanism and cooperating with contacts on said commutator.

16. A switch actuating mechanism comprising a ratcheting plate, a cooperating rotatable and axially movable spring pressed ratcheting member, a pivoted actuating member, and means operative thereby for actuating said movable ratcheting member comprising oppositely extending cams on said actuating member and oppositely extending cams on said movable ratcheting member overlying said first cams and each having depending oppositely inclined portions each engaged by one of the cams on said actuating member.

17. In a switch, actuating mechanism having an actuating member provided with an upstanding portion, cooperating ratcheting mechanism including an angularly and vertically movable ratcheting member movable upon operation of said actuating member and having a projection movable with said vertically movable member and disposed adjacent said upstanding portion, a single coiled spring disposed around the axis of said movable ratcheting member and compressed upon vertical movement thereof and having opposite ends extending on opposite sides of both said portion and projection, and movable contact means engaged and actuated by said projection and said spring.

18. A switch actuating mechanism comprising a holding plate, a cooperating rotatable and axially movable spring pressed holding member, an actuating member, and means operative thereby for actuating said movable holding member comprising laterally and oppositely extending cams on said actuating member and laterally and oppositely extending cams on said movable holding member having depending oppositely inclined portions between which said first mentioned laterally extending cams are disposed.

19. A switch actuating mechanism comprising a ratcheting plate, a cooperating rotatable and axially movable spring pressed ratcheting member having peripherally projecting portions, a pivoted actuating member, and means operative thereby for actuating said movable ratcheting member, said ratcheting plate having an axial aperture therein and ratchet notches communicating with said aperture and receiving said peripherally projecting portions of said spring pressed ratcheting member in different positions, and said last mentioned means having a rotatable cam means disposed in said aperture and operating said movable ratcheting member.

20. An electric switch having contact mechanism including contacts movable about a vertical axis, ratcheting mechanism comprising a stationary ratchet member and a movable ratchet member having projecting portions cooperating with said stationary member for positioning said contacts in different positions, actuating mechanism including an actuating arm having an actuating portion located between said stationary and movable ratchet members and an operating arm projecting outwardly between the projecting portions of said movable ratchet member and movable in reverse directions relative thereto.

to for releasing said movable ratchet member, and an actuating spring having an operative connection between said movable ratchet member and said actuating arm for moving said 5 ratchet member in the direction of movement of said actuating member following the release of the former by said actuating member.

21. An electric switch having contact mechanism including contacts movable about a vertical axis, ratcheting mechanism comprising a stationary ratchet member and a movable ratchet member having projections cooperating with said stationary ratchet member for positioning said contacts in different positions, an actuating arm 10 extended between said stationary and movable ratchet members and movable in reverse directions for releasing said movable ratchet member, said movable ratchet member having its projections disposed on opposite sides of said actuating arm, and an actuating spring having an operative connection between said movable ratchet member and said actuating arm for moving said movable ratchet member when the latter is released. 15

22. In an electric switch, a casing having a fixed spindle, contact mechanism including contacts movable about said spindle, ratcheting mechanism comprising a stationary ratchet member and a vertically movable ratchet member 20 cooperating with said stationary member for positioning said contacts in different positions, actuating mechanism including an actuating member pivotally mounted on said spindle having its actuating portion located adjacent said movable ratchet member on the opposite side thereof from said movable contacts and movable in reverse directions for releasing said movable ratchet member, and an actuating spring having an operative connection between said movable 25 ratchet member and said actuating member for moving said movable ratchet member whenever the latter is released by said actuating mechanism. 30

23. In an electric switch, a casing having a fixed spindle, stationary and movable contact mechanisms, ratcheting mechanism comprising a stationary ratchet member and a relatively vertically movable ratchet member cooperating 35 with said stationary member for positioning said contact mechanism in different positions, actu- 40

ating mechanism including an actuating arm movable about said fixed spindle and having an upstanding portion and cam portions on opposite sides of said spindle for raising said movable ratchet member to release the latter from said 5 cooperating member, and a spring operatively connected between the upstanding portion of said actuating member and said movable ratchet member constantly urging said ratchet members into engagement and moving said movable ratchet member and movable contact mechanism in the direction of movement of said actuating member following releasing of said ratchet member. 10

24. In a switch, actuating mechanism having an actuating member provided with an upstanding portion, cooperating ratcheting mechanism including an angularly and vertically movable ratcheting member movable upon operation of said actuating member and having a projection 20 movable with said vertically movable member and disposed adjacent said upstanding portion, a single coiled spring disposed around the axis of said movable ratcheting member and compressed upon vertical movement thereof and having opposite ends extending on opposite sides of both said portion and projection, movable contact means engaged and actuated by said projection and said spring, and a stationary stud extending axially through the switch and having all of the 25 movable parts of the switch rotatable about the axis of said stud. 30

25. In a switch, a frame of conducting material, a cover plate of insulating material carried by said frame, a disc-like commutator member of 35 insulating material swiveled in said frame to turn in a plane parallel to said cover plate, contact members on said commutator member having interconnected contact arms projecting peripherally from opposite faces of said member 40 and providing pairs of opposing contacts, terminal members on said cover member having portions extending therethrough and into said frame and provided with inturned contact portions adapted to extend between and bridge opposing contacts of said commutator member, and means for swinging said commutator member with a snap action. 45
